UNITED STATES PATENT OFFICE.

JOHN MONTGOMERY, OF NEW YORK, N. Y.

GARMENT-SLEEVE.

1,178,664.

Specification of Letters Patent. Patented Apr. 11, 1916.

Application filed April 9, 1915. Serial No. 20,155.

To all whom it may concern:

Be it known that I, JOHN MONTGOMERY, a citizen of the United States of America, residing at New York city, Manhattan borough, county and State of New York, have invented certain new and useful Improvements in Garment-Sleeves, of which the following is a full, clear, and exact description.

10 This invention relates to an improvement in garment-sleeves, but pertains more particularly to the cuff-portion of such sleeves commonly known as pick-up cuffs.

15 The object of my invention is to provide a sleeve with a cuff-portion that can be extended, to make the sleeve longer, by merely severing a line of stitches which are hidden from view, that is to say, the stitches do not appear upon the outer surface of the 20 cuff, but are located beneath the outer layer and serve to secure the cuff to the material of the sleeve.

25 A further feature of improvement is the manner of securing the inner end of the turned-in portion of the cuff which is permanently secured.

30 A further feature of my improvement resides in the lining of the sleeve, the outer end thereof being permanently secured to the turned-in portion of the cuff.

35 The features referred to will be more particularly hereinafter described and finally pointed out in the appended claims, reference being had to the accompanying drawing, forming part hereof, wherein

Figure 1 is a perspective view of a sleeve having my improved cuff attached thereto; Fig. 2 is an enlarged longitudinal sectional view thereof; and Fig. 3 is a similar view 40 of a portion of the cuff and sleeve, the cuff being illustrated as having been extended or lengthened, and integral with the sleeve.

45 In the drawing a portion of the sleeve of a coat or the like is designated by 1, while 2 designates my improved extensible cuff. As will be seen in Fig. 1 the cuff 2 and sleeve 1 are not made in one piece, but are two separate pieces secured together by three separate and distinct lines of stitches 3, 4 and 5. In case of thin fabric, however, the cuff may be formed integral with or as a continuation of the sleeve fabric, as shown 50 in Fig. 3. The stitches 3, 4 and 5 pass through the turned-in ends 6 of the cuff and lower end 7 of the sleeve 1.

55 One of the features of my improvement

is the securing of the lower turned-in portion 8 of the cuff to the turned-in upper portion 6 thereof, as at 9; but this particular point of securement may be varied.

60 A still further feature of improvement resides in the lining 10 which at its lower end 11 is secured by stitches 12 to the turned-in lower portion 8 of the cuff 2. To permit of the lengthening of the lining 65 when the cuff is lengthened, I double or fold the lining upon itself, as at 13, and apply two separate lines of stitches 14 and 15 to said folded portion.

70 The object of securing the end of the turned-in lower portion 8 of the sleeve to the turned-in upper end 6 of the cuff and end of sleeve 1, is to prevent the member 8 of the sleeve from creeping to destroy the crease 16 at the lower end of the cuff. In 75 this respect my improved cuff differs from the ordinary cuff which has its turned-in lower portion secured to its outer member, which corresponds to the outer member 17 of the cuff herein illustrated.

80 My improved cuff consists of a strip of fabric folded in at the ends to form a complete loop, the ends of the loop being secured together. The cuff is first secured to the sleeve by the stitches 3, 4 and 5; the 85 material is then folded over as at 18 to form the member 17. The lower end 8 is then turned in and secured, by the stitches 9, to the opposite turned-in end 6 and sleeve 1, after which the lining 10 is placed in the 90 sleeve.

95 To lengthen the sleeve the line of stitches 5 will be severed by passing a knife, or other cutting device, into the gap 19. The stitches 14 in the lining 10 will then be severed, after which the cuff can be extended or pulled outwardly as shown in Fig. 3. It will be noted that to perform the operation of lengthening the sleeve, by extending the cuff, the stitches 12, which secure 100 the lower end of the lining to the cuff, have not been disturbed. When the cuff is pulled down the lining will follow by unfolding at 13. After this operation has been performed, the cuff can be pressed by 105 ironing, after which the cuff will lie perfectly smooth, no stitches appearing on the outer surface thereof. It will also be noted that to extend the cuff the stitches 9 will not have to be disturbed. When the cuff is extended to increase the length of the sleeve 110 the turned over portion 6 of the cuff will

become shorter and the portion 8 longer and the secured together inner ends of said turned over portion will not change their position relative to the lower end of the 5 sleeve 1.

Having now described my invention, what I claim and desire to secure by Letters Patent is:

1. In combination with a garment-sleeve, 10 a cuff consisting of a strip of fabric folded over and turned inwardly at each end, said ends being secured together, and a plurality of separate seams of stitching securing the upper folded end of the cuff to the lower end 15 of the sleeve.
2. In combination with a garment-sleeve, a cuff consisting of a strip of fabric folded over and turned inwardly at each end, said ends being secured together, a plurality of 20 separate seams of stitching securing the upper folded end of the cuff to the lower end of the sleeve, and a lining for said sleeve and cuff, said lining being doubled over upon itself adjacent the lower end of 25 the sleeve, said lining at its lower end being secured to the turned over lower portion of the cuff.
3. In combination with a garment-sleeve, 30 a cuff consisting of a strip of fabric folded over and turned inwardly at its ends, said ends being secured together, thereby forming a cuff consisting of an outer and inner member having a space therebetween and a plurality of independent seams of stitching 35 to fasten the sleeve and inner member of the cuff together and arranged to permit said cuff to be extended when one or more of the seams are severed.
4. In combination with a garment-sleeve, 40 a cuff consisting of a strip of fabric folded

over and turned inwardly at its ends, said ends being secured together, thereby forming a cuff consisting of an outer and inner member having a space therebetween, a plurality of independent seams of stitching 4 to fasten the sleeve and inner member of the cuff together and arranged to permit said cuff to be extended when one or more of the seams are severed, and an extensible lining for said cuff and sleeve, the lower 5 end of said lining being secured to the lower folded over portion of the cuff.

5. In combination with a garment-sleeve, a cuff consisting of a strip of fabric folded over and turned inwardly at its ends, said 55 ends being secured together, thereby forming a cuff consisting of an outer and inner member having a space therebetween, means to permanently fasten the secured together inner ends of the turned-in cuff members 60 to the lower end of the sleeve, and independent means to releasably secure the remainder of the upper turned over cuff member to the sleeve.

6. In combination with a garment-sleeve, 65 a cuff having both of its ends turned in, one of the turned-in ends being secured to the sleeve by a plurality of independent rows of stitching, and a lining for said sleeve and cuff secured at its free end to the inturned 70 lower portion of the cuff, said lining being doubled upon itself and held by one or more independent rows of stitching.

Signed at New York city, N. Y. this 8th day of April, 1915.

JOHN MONTGOMERY.
